CLAIM

The ornamental design for a game board, as shown and described.

DESCRIPTION

Reference is made to related U.S. patent application Ser. No. 20/265,070 (U.S. Pat. D550,295) filed Aug. 25, 2006 and issued Sep. 4, 2007.

FIG. 1 is a top plan view showing the ornamental design of a game board; and,

FIG. 2 is a left side view, with the right, front and rear sides being mirrored view.

The broken lines shown in FIG. 1 depict environment only, and form no part of the claimed design.

1 Claim, 1 Drawing Sheet
